ELECTRIC SWITCH LOCK

William C. McWhirter, Wilkinsburg, and Glen V. Jefferson, Edgewood, Pa., assignors to The Union Switch & Signal Company, Swissvale, Pa., a corporation of Pennsylvania

Application January 30, 1946, Serial No. 644,338

7 Claims. (Cl. 246—159)

1

Our invention relates to electric switch locks, and particularly to electric switch locks of the type comprising a manually operated locking plunger cooperating with a lock rod attached to the switch points to lock the switch in its normal position, and electrical means effective when de-energized to prevent operation of said locking plunger away from its locking position.

One well-known form of electric lock of the type described is mounted in a housing provided with a main front door and an auxiliary rear door. The main front door when opened gives access to the operating handle for the locking plunger, while the auxiliary door when opened gives access to the lock magnet, to a circuit controller operated by the plunger lock handle, to various circuit controlling contacts controlled by the lock magnet, etc. The main door is normally locked in its closed position by means of a pad-lock which can only be opened by the trainman's usual switch key, while the auxiliary door is normally locked in its closed position by a lock requiring a special key furnished only to maintainers. A locking segment is operatively connected with the lock handle and is so arranged that the armature of the lock will enter a notch provided in the locking segment when and only when the lock magnet is deenergized and the plunger lock handle is in its locking position in which the switch is locked, thus preventing the premature closing of any circuits controlled by the lock armature. The main door is also provided with means which cooperate with the lock handle to prevent the door from being closed unless the handle is moved to a position where it is free to return to its full locked position.

Locks of the type described usually also include a so-called forced drop feature comprising spring means tensioned by the closing of the main door, and effective to apply a spring force to the lock armature when the main door is closed to force the armature to its locking position, and to prevent damage to the parts due to vibration, as well as an emergency release push button access to which can only be had by breaking a telltale seal. The push button is effective when operated to move the lock armature to its operated position to permit emergency operation of the switch in the event of failure of the usual lock energizing circuit for any reason, and normally controls contacts which are included in the circuits for the signals in such manner that all signals governing traffic movements over the switch will be placed at stop before the switch can be unlocked under emergency conditions.

2

One object of our present invention is to provide novel means whereby, when the emergency push button in a lock of the type described is operated, it will become latched in a position in which all signals which are placed in their stop positions by the operation of the push button will be retained in their stop positions until the latch is manually released by a maintainer.

Another object of our invention is to combine the forced drop and emergency release features of an electric lock of the type described into a unitary structure which is economical to build and assemble, and which provides over prior structures certain operating advantages pointed out more fully hereinafter.

Other objects and characteristic features of our invention will become apparent as the description proceeds.

We shall describe one form of electric lock embodying our invention, and shall then point out the novel features thereof in claims.

In the accompanying drawings, Fig. 1 is a top plan view showing a railway switch provided with an electric lock embodying our invention. Fig. 2 is an end view partially sectioned of the switch and lock shown in Fig. 1. Fig. 3 is a front view with the door open of the lock shown in Figs. 1 and 2. Fig. 4 is a vertical sectional view of the lock shown in Fig. 3 taken substantially on the line IV—IV of Fig. 3. Figs. 5 and 6 are left-hand end and top views, respectively, of the lock shown in Fig. 4 with certain parts removed or broken away to better illustrate the construction of the remaining parts.

Similar reference characters refer to similar parts in each of the several views.

Referring to the drawings, a lock embodying our invention comprises a suitable casing 1 mounted on the upper end of a lock support 2 secured in any suitable manner, as by lag screws 3, to two adjacent crossties 4 at one side of a railway switch S. The casing 1 is provided with front and rear doors 5 and 6 and is divided by means of a partition wall 7 into front and rear compartments 8 and 9 for a purpose which will appear presently.

The switch S is of the usual and well-known construction, and comprises a fixed rail 10 and a movable switch point 11. The movable switch point 11 is shown in its normal position in which it engages the fixed rail 10, but is adapted to be at times moved to a reverse position in which it is spaced from the fixed rail 10 by any suitable form of switch throwing device not shown. In actual practice, the switch throwing device will

usually comprise a switch stand of conventional construction.

A lock rod 12 is attached at one end to the switch point 11 and is slidably supported at the other end in a suitable guideway 13 provided in the bottom of the lock support 2. Formed in the lock rod 12 is a hole 12a which, when the switch point 11 occupies the normal position shown, is adapted to at times receive a locking plunger 14 forming part of the electric lock, to lock the switch point 11 in its normal position.

The locking plunger 14 is pivotally attached to the lower end of an up-and-down rod 15 which extends upwardly with clearance through the lock support 2 and is pivotally connected at its upper end to a crank 17 mounted on an operating shaft 18 journaled in suitable bearings 19 provided in a supporting bracket 20 secured to the bottom of the casing 1 within the rear compartment 9 of the casing. The front end of the shaft 18 extends with clearance through a hole 21 provided in the partition wall 1, and has secured thereto within the outer compartment 8 an operating handle 22 by means of which the shaft can be rotated when and only when the front door 5 is open. The front door 5 is arranged to be locked in its closed position by inserting a padlock 23 (see Fig. 2) through an eye 24 which is provided on the door 5 and which cooperates with a hasp 25 pivotally attached to the casing 1 adjacent the side of the door 5 which swings outwardly when the door is open. The operating handle is adapted to be swung between two extreme positions determined by stop lugs 26 and 27 provided on the outer side of the partition wall 1, and the parts are so proportioned that when the handle is swung to the extreme position in which it engages the stop lug 26, which position we shall designate its locking position, the locking plunger 14 will enter the hole 12a in the lock rod 12 and lock the switch point 11 in its normal position, but that when the handle 22 is swung to its opposite extreme position in which it engages the lug 27, which later position we shall designate its unlocking position, the locking plunger 14 will then be lifted clear of the lock rod 12. It is desired to prevent the front door 5 from being closed except when the operating handle 22 is moved to its locking position, and to this end an arcuate lug 28 is provided on the door 5 in such a position that it will cooperate with the operating handle to prevent closure of the door if the handle is not in its locking position.

A drum type controller 30 is mounted on the operating shaft 18, and is provided with a plurality of contact bands 31 which cooperate with pairs of contact fingers 32 and 33 disposed on opposite sides of the shaft to form circuit controlling contacts responsive to the position of the shaft. The contact bands are secured at their ends within longitudinal slots provided in the insulating drum of the controller, and it follows that by assembling the bands in the proper positions on the drum and by varying the lengths of the bands the contacts may be made to open or close in any desired position of the shaft. The contact fingers 32 and 33 are secured by means of terminal posts 34 to insulating terminal boards 35 secured at their ends to supports 36 provided on the supporting bracket 20.

A locking segment 40 is formed integrally with the crank 17, and this segment is provided with a notch or shoulder 41 which cooperates with a locking dog 42. The locking dog 42 is secured by means of a finger 43 to a vertically swinging ar-

mature supporting member 44, and is maintained against lateral displacement by a slotted guide member 45 (Fig. 5) formed integrally with the supporting frame 20. The armature supporting member 44 is pivotally supported intermediate its ends by means of trunnions 46 journaled at their ends in trunnion screws 46a adjustably screwed through depending lugs 47a provided on a supporting plate 47 bolted to the upper end of the supporting frame 20, and carries an armature 48 which cooperates with pole pieces 49 formed on the lower ends of the cores 50 of an electromagnet L. The cores 50 are mounted in parallel spaced relation in the supporting plate 47 and are connected together at their upper ends by a backstrap 51. Surrounding the cores are coils 52 which will usually be connected in series in such manner as to produce cumulative fluxes in the cores when these coils are energized, and which coils together constitute the energizing winding for the electromagnet.

The notch 41 in the locking segment 40 is so disposed that it will align with the locking dog 42 when and only when the operating handle 22 is rotated to its locking extreme position, and the parts are so proportioned that when the notch 41 is in alignment with the locking dog 42, the dog 42 will enter the notch due to gravity or will be lifted clear of the notch according as the electromagnet L is then deenergized or energized. It follows that when the operating handle 22 occupies its locking position, it cannot be moved away from this position unless the electromagnet L is then energized to lift the locking dog 42 out of the notch 41, or unless the locking dog is manually lifted out of the notch in a manner which will be described in detail hereinafter. The energization of the electromagnet L will usually be effected as the result of the closing of a remotely controlled circuit which is rendered available by the opening or closing of contacts actuated by the opening of the front door 5, as will appear hereinafter.

The armature supporting member 44 extends rearwardly past its point of pivotal support and has secured thereto at its rear end an adjustable counterweight 53 the function of which is to counterbalance the weight of the armature and the locking dog 42 a sufficient amount to enable the locking dog to be lifted out of the notch 41 in response to a reasonable degree of energization of the electromagnet L.

The locking dog 42 is operatively connected by means of a vertical rod 55 (Figs. 3 and 4) with a pivoted indicator 56 visible through a window 57 in the partition wall 1 of the casing 1. This indicator may assume a variety of forms, but in the form here shown consists of a pivoted arcuate member 58 positioned behind the window 57 in such manner that it will indicate locked or unlocked according as the locking dog 42 is within the notch 41 in the locking segment 40 or is swung upwardly to the position in which it is clear of the locking segment.

In order to provide a means for indicating at a remote point the locked or unlocked condition of the switch the armature supporting member 44 is operatively connected by means of a movable link 60 with two flexible contact fingers 61 and 62 which cooperate with fixed contact fingers 63 and 64 to form contacts 61-63 and 62-64. The contact fingers 61, 62, 63 and 64 are secured by means of terminal posts 65, 66, 67 and 68, respectively, to an insulating terminal board 69 mounted on the rear end of the supporting plate 47. As

shown, the parts are so arranged that the fingers will be moved to the positions in which the contacts formed thereby will be closed or open according as the locking dog 42 occupies its locking or its unlocking position, but it should be pointed out that where desirable for special applications the fingers of either one or both of the contacts may be reversed so that these contacts will be open or closed according as the dog 42 occupies its locking or its unlocking position.

The portions of the lock thus far described are of well-known construction and the operation as a whole of these portions of the lock will be apparent from an inspection of the drawings without further detailed description.

According to our present invention, the lock is provided with a so-called "forced drop anti-vibration mechanism" combined into a unitary structure with a so-called "mechanically latched emergency release mechanism," which mechanisms we shall now describe.

The forced drop anti-vibration mechanism in the form here shown comprises an operating rod 70 (see Fig. 4) slidably supported in aligned holes 71 and 72 formed in the opposite sides 73a and 73b of a rectangular supporting bracket 73 secured by means of machine screws 74 to a laterally projecting lug 75 formed on the supporting plate 47. The rod 70 extends outwardly with some clearance through a hole 76 provided in the partition wall 7, and is constantly biased to an outer position by means of a compressed coil spring 77 disposed on the rod between the side 73a of the frame 73 and a rigid arm 78 which is pinned at one end to the rod 70. The outer end of the rod 70 cooperates with the head of a stud 79 adjustably mounted in a boss 80 provided on the inner face of the main door 5 of the casing 1. The stud 79 is so adjusted that when the door 5 is closed, the head of the stud will engage the rod 70 and will force it inwardly in opposition to the bias of the spring 77 to an inner position in which the inner end of the arm 78 is spaced a slight distance from the side 73a of the bracket 73.

A lever arm 81 (Figs. 4 and 6) is pivotally mounted at one end on a pivot pin 82 secured to the supporting plate 47 and is pivotally connected at one end by means of a pin and slot connection to the inner end of the rigid arm 78. A leaf spring 81a of phosphor bronze or the like is secured to one side of the arm 81, and this spring cooperates with an upstanding arm 83 provided on the armature supporting member 44 in such manner that when the push rod 70 is moved inwardly to its inner position by the closing of the door, the spring 81a will engage the arm 83 and will exert a force on this arm sufficient to urge the locking dog to its full locking position and to retain it there irrespective of vibrations which may be transmitted to the lock due to passing trains, but that, when the push rod is permitted to move to its outer position due to the opening of the door 5, the spring 81a will then be swung clear of the arm 83 a sufficient amount to prevent it from exerting any force on the armature supporting member 44 which would oppose that due to the energization of the electromagnet. Attached to the outer end of the rod 70 is a flexible weatherproof covering 84 which acts to prevent the entry of moisture into the casing 1 through the opening 76 around the rod 70.

The rod 70 cooperates at its inner end with a movable contact finger 85 secured by means of terminal posts 86 and 87 to one side of the terminal board 68. The finger 85 is insulated from

the rod 70 by an insulating strip 88 secured to the finger and cooperates with a fixed contact finger 89 to form a contact 88-89. The finger 89 is secured to the opposite side of the terminal board from the finger 85 by means of the terminal posts 86 and 87 and is insulated from the terminal post 86 but is electrically connected with the terminal post 87. The finger 85 is insulated from the terminal post 87 but is electrically connected with the terminal post 86. It will be apparent, therefore, that the posts 86 and 87 not only provide a means for securing the contact fingers to the terminal board but also provide a means for establishing electrical connections with these fingers. The parts are so arranged that the contact 85-89 will be closed or open according as the rod 70 occupies its inner position or is moved to its outer position. This contact may be used to indirectly control the energization of the electromagnet L or for any other desired purpose.

It should be noted that while the contact 85-89 as shown is arranged to be closed when the door is closed and open when the door is open, this contact may readily be reversed in accordance with well-known practice.

The emergency release mechanism in the form here shown comprises a push rod 90 slidably supported in the sides 73a and 73b of the supporting bracket 73 above the operating rod 70. This rod is formed with an offset portion which extends outwardly through a clearance hole 91 provided in the partition wall 7 and has secured to its outer end a push button knob 92. The rod is biased to an outer position by means of a compressed coil spring 93 which surrounds the rod between the side 73a of the bracket 73 and a collar 94 pinned to the rod. It may be sealed in this position by means of a blocking arm 95 which is attached at one end by means of a pin 96 to the outer side of the partition wall 7. The arm 95 is provided with a slotted portion 95a which, when the arm is rotated to the extreme position shown, extends between the partition wall and the push button in such manner that it is then impossible to move the push button inwardly from its outer position. The blocking arm, however, may be rotated to another position in which the slotted portion 95a is withdrawn from behind the push button. When the blocking arm occupies its blocking position, it engages a stud 97 secured to the partition wall 7, and this stud is provided with a hole which aligns with a hole in the blocking arm to enable a seal wire 98 to be passed through these parts in such manner that the blocking arm can only be rotated away from its blocking position by breaking this seal wire.

The push rod 90 is provided adjacent its inner end with a collar 100 carrying a flexible or spring rod 101 which cooperates with the upstanding arm 83 on the armature supporting member 44 at the opposite side of the arm from the spring 81a. The parts are so proportioned that when the push button 92 is moved to its inner position, the flexible rod 101 will engage the arm 83 and will move the arm far enough to lift the locking dog clear of the notch 41 in the locking segment 40 if the flexible spring 81a is out of engagement with the arm, as will be the case when the door 5 is open. However, if the door 5 is closed, the force exerted on the arm 83 by the flexible rod 101 will be insufficient to overcome the opposing force due to the spring 81a.

The collar 100 cooperates with a latching member 102 secured by means of a flexible strip 103

to the upper side of the supporting frame 73 in such manner that when the push button 92 occupies its outer extreme position, the latch will rest on top of the collar, but that when the push button is moved to its inner extreme position, the latch will then move downwardly due to the bias of the flexible supporting strip 103 to a position behind the collar 100 and will thus act to latch the push button in its inner extreme position. The outer end of the flexible supporting strip 103 is bent upwardly and outwardly to provide a finger grip 103a by means of which the latch may be restored to its unlatching position after it has once been moved to its latching position. It will be obvious that in order to gain access to the latch it is necessary to open the rear door 6 of the mechanism case and since this case is locked by a lock which can only be opened by the maintenance's key, it is impossible for a trainman after he operates the pushbutton to restore it to its unlatched condition. To prevent damage to the latch by moving it upwardly an excessive amount when restoring the latch to its unlatched position after it has been moved to its latched position, a screw stop 104 is provided. The shank of this screw extends through a clearance hole in the latch and is screwed into a tapped hole provided in the upper side of the supporting bracket 73.

The push rod 90 cooperated at its inner end with a contact comprising a flexible contact finger 105 and a fixed contact finger 106. These contact fingers are secured to the opposite sides of the terminal board 69 by means of terminal posts 107 and 108 in the manner similar to that in which the contact fingers 85 and 89 are secured to the terminal board and are so arranged that the contact formed thereby will be closed or open according as the push button occupies its outer or its inner extreme position.

The operation of the lock as a whole is as follows: When the switch point 11 occupies its normal position as shown in Fig. 1, both doors of the electric lock are normally locked in their closed positions and the switch is accordingly locked by engagement of the locking plunger 14 with the notch 12a in the lock rod 12. Assuming now that a trainman desires to reverse the switch S, and has obtained the necessary permission to do so, he will remove the padlock 23 from the hasp 24 on the door 5 and will then open the door. The opening of the door will permit the push rod 70 to move to its outer position and will thus cause the contact 85-89 to move from its closed to its open position. If conditions are such that it is safe to reverse the switch without endangering traffic, the opening of the contact 85-89 will ordinarily cause the electromagnet L to become energized by virtue of circuits forming no part of my present invention, and the energization of this electromagnet will move the armature 48 to its attracted position. This movement, in turn, will lift the locking dog 42 out of the notch 41 in the locking segment 40 and will thus unlock the lever 22. This movement of the armature will also operate the contacts 61-63 and 62-64 and will thus provide a means for indicating at a distance control point that the electric lock has functioned to unlock the switch. The movement of the armature to its attracted position will further act through the armature supporting member 44 and the rod 55 to move the switch indicator from the position in which it reads "locked" to the position in which it reads "unlocked." As soon as this indicator moves to this latter posi-

tion, the trainman knows that the lever is unlocked, and he will then operate the lever 22 from its locking position to its unlocking position whereupon he may reverse the switch points by means of the usual switch stand or other switch throwing device. The operation of the lever to its unlocking position will work the contacts of the drum controller connected therewith and will thus provide a means for conditioning any circuits controlled thereby in accordance with the positions which the parts then occupy.

After the switch has been reversed in the manner just described and it is desired to restore it to the position shown, the trainman will first return the switch point to its normal position by means of the switch stand and will then restore the lever 22 to its locking position. The movement of the lever to its locking position will cause the locking plunger to reenter the notch 12a in the lock rod and will thus again lock the switch point 11 in its normal position. As soon as the switch point has been locked in its normal position, the trainman may then close the door and replace the padlock 23 in the hasp 24. The closing of the door will move the operating rod 70 inwardly against the bias of the spring 77 which latter movement, in turn, will close the contact 85-89 whereupon the electromagnet L will become deenergized through controls not shown. The inner movement of the push rod will also act through the arm 78 and lever 81 to cause the spring 81a to exert a force on the arm 83 of the armature supporting member 44 which force will act to insure that the locking dog will reenter the notch 41 in the locking segment 40 and will be prevented from vibrating within the notch.

We shall now assume that a trainman desires to reverse the switch in the manner previously described but that when he opens the door 5, the electromagnet fails to become energized due to some unusual condition such for example as a power failure, or a failure of some part of the energizing circuit for the magnet to function as intended. Under these conditions the trainman after obtaining permission so that his action is recorded by proper authority will remove the seal 98 and will then rotate the blocking arm 95 upwardly from its blocking position to a position in which it is out of the path of movement of the emergency release push button 92. As soon as the blocking arm has been rotated to this position, the push button 92 may be operated. Operation of this push button will first cause the contact 105-106 to become opened and will then cause the latch 102 to drop down behind the collar 100 and thus latch the push button in its inner extreme or operated position. The inward movement of the push rod will also act through the spring rod 101 to exert a force on the arm 83 carried by the armature supporting member 44 sufficient to lift the locking dog from the notch 41 in the locking segment 40. It will be remembered that the opening of the door 5 permits the operating rod 70 to move outwardly due to the bias of the spring 77 so that when the push rod 90 is moved inwardly under the conditions just described, the leaf spring 81a will have been rotated to a position in which it will not oppose the motion of the armature supporting member by the spring rod 101. It follows that it is possible for the locking dog to be moved to its unlocking position under these conditions without interference by the forced drop mechanism of the lock. The parts are so designed and so proportioned that the movement which the spring rod 101 will

have imparted to the arm 83 when the push button has been moved just far enough to open the contact 105-106 and permit the latch to drop down behind the collar 100 will not be sufficient to completely lift the locking dog out of the notch 41 so that in order to lift the dog clear of the notch it will be necessary for the trainman to push the push button 92 to the extreme inner end of its stroke. The reason for this proportioning of the parts is to make it impossible to obtain an unlock of the switch until the signals have been placed in their restrictive positions and the contacts latched open. As soon as the locking dog has been lifted clear of the notch the trainman may then proceed to unlock and reverse the switch in the manner previously described. When the emergency push button has become latched in the manner previously described it remains latched against further manipulation by the trainman. The contact controlled by the push button will normally be employed to control the signals governing traffic movements over the switch and it follows that the latch mechanism provides a means for guarding against a dangerous condition due to carelessness on the part of a trainman since while the switch may be restored to its normal position and relocked in this position it is impossible for the trainman to unlock the push button. The fact that it is necessary for the trainman to break a seal in order to operate the push button leaves a telltale that the lock has been operated under emergency conditions by proper authority so that the maintainer will immediately be notified to restore the conditions to normal. The maintainer will thereupon open the rear door and lift the latch clear of the collar 100 which will permit the push button to return to its outer position. As soon as the push button has been returned to its outer position the maintainer will then restore the blocking arm to its blocking position and will seal it in this position by a new seal. Both doors may then be returned to their normal locked positions and all parts will be restored to their normal operating positions in which they are illustrated in the drawing.

It should be pointed out that the design of the spring rod 101 is such that it is possible after the push button has been moved to its emergency release position and latched there to close the main door of the case in the normal manner to thereby cause the normal forced drop and anti-vibration force exerted by the spring 81a to be applied to the armature.

It should also be pointed out that after the emergency release push button has been once latched in its operated position and the door 5 is opened, the locking dog is held in locked position unless the trainman pushes the button 92 in order to again cause the locking dog to move to its unlocking position. During this operation if the wayside signals are controlled by the contacts 105 and 106 as will normally be the case, these signals will continue to display their most restrictive indications. If therefore becomes a matter of urgent maintenance that when it has once been found necessary to operate the emergency release mechanism immediate steps should be taken to restore all parts to their normal positions by the maintainer.

Although we have herein shown and described only one form of electric lock embodying our invention, it is understood that various changes and modifications may be made therein within the

scope of the appended claims without departing from the spirit and scope of our invention.

Having thus described my invention, what we claim is:

1. A locking device for railway traffic controlling apparatus comprising a locking segment, manually operable means connected with said segment for moving said segment between two extreme positions, a locking dog adapted to engage said segment in one extreme position to prevent movement of said segment away from such extreme position, electrically controlled means effective when energized for moving said locking dog to an unlocking position, an emergency release push button biased to one position, means controlled by said push button and effective when said push button is moved from said one position to another position to move said locking dog to its unlocking position, latch means effective when said push button is moved part way to said other position for subsequently preventing said push button from returning to its one position until said latch means is manually operated to release said push button, and contact means selectively responsive to the latched and unlatched positions of said push button.

2. A locking device for railway traffic controlling apparatus comprising a locking segment, manually operable means connected with said segment for moving said segment between two extreme positions, a locking dog adapted to engage said segment in one extreme position to prevent movement of said segment away from such extreme position, electrically controlled means effective when energized for moving said locking dog to an unlocking position, an emergency release push button biased to one position, means controlled by said push button and effective when said push button is moved from said one position to another position to move said locking dog to its unlocking position, latch means effective when said push button is moved part way to said other position for subsequently preventing said push button from returning to its one position until said latch means is manually operated to release said push button, contact means operated by movement of said push button from its one to its latched position, a blocking lever movable between a normal position in which it prevents operation of said push button away from its one position and another position in which it is out of the path of movement of said push button, and a removable seal for sealing said blocking lever in its normal position, said seal being constructed to be destroyed by its removal to provide a telltale when said seal is removed.

3. A locking device for railway traffic controlling apparatus comprising a casing provided with front and rear doors and divided by means of a partition wall into front and rear compartments, a traffic controlling shaft disposed in said rear compartment and connected with an operating lever disposed in said front compartment, said operating lever being movable between locking and unlocking positions, means preventing the closing of said front door except when said lever occupies its locking position, a locking segment connected to said shaft, a locking dog movable between locking and unlocking positions and effective when said lever and said dog both occupy their locking positions to engage said segment to prevent movement of said lever away from its locking position, electrically controlled means effective when energized to move said locking dog to its unlocking position, an operating rod

biased to an outer position and movable to an inner position in response to the closing of said front door, means connected with said operating rod and effective when said operating rod is moved to its inner position to exert a force on said locking dog which biases it to its locking position, a push rod movable between inner and outer positions, a push button secured to said push rod within said outer compartment, means biasing said push rod to its outer position, other spring means connected with said push rod and effective when said push rod is moved to its inner position to exert a force on said locking dog which biases it to its unlocking position, latch means effective when said push rod is moved part way to its inner position for preventing it from returning to its outer position, said latch means being accessible only through the rear door of said casing, and contact means selectively responsive to the latched and unlatched positions of said push rod.

4. A locking device for railway traffic controlling apparatus comprising a casing provided with front and rear doors and divided by means of a partition wall into front and rear compartments, a traffic controlling shaft disposed in said rear compartment and connected with an operating lever disposed in said front compartment, said operating lever being movable between locking and unlocking positions, means preventing the closing of said front door except when said lever occupies its locking position, a locking segment connected to said shaft, a locking dog movable between locking and unlocking positions and effective when said lever and said dog both occupy their locking positions to engage said segment to prevent movement of said lever away from its locking position, electrically controlled means effective when energized to move said locking dog to its unlocking position, an operating rod biased to an outer position and movable to an inner position in response to the closing of said front door, spring means connected with said operating rod and effective when said operating rod is moved to its inner position to exert a force on said locking dog which biases it to its locking position, a push rod movable between inner and outer positions, a push button secured to said push rod within said outer compartment, means biasing said push rod to its outer position, other spring means connected with said push rod and effective when said push rod is moved to its inner position to exert a force on said locking dog which biases it to its unlocking position, latch means effective when said push rod is moved part way toward its inner position for preventing it from returning to its outer position, said latch means being accessible only through the rear door of said casing, contacts operated by said push rod to one position or another according as said push rod occupies its outer position or is moved toward its inner position at least as far as its latched position, a blocking lever movable between a normal position in which it cooperates with said push button to prevent operation of said push button away from its outer position and an operated position in which it is out of the path of movement of said push button, and a removable seal for sealing said blocking lever in its normal position, said seal being constructed to be destroyed by its removal.

5. A locking device for railway traffic controlling apparatus comprising a casing provided with front and rear doors and divided by means of a partition wall into front and rear compartments,

a traffic controlling shaft disposed in said rear compartment and connected with an operating lever disposed in said front compartment, said operating lever being movable between locking and unlocking positions, means preventing the closing of said front door except when said lever occupies its locking position, a locking segment connected to said shaft, a locking dog movable between locking and unlocking positions and effective when said lever and said dog both occupy their locking positions to engage said segment to prevent movement of said lever away from its locking position, electrically controlled means effective when energized to move said locking dog to its unlocking position, an operating rod biased to an outer position and movable to an inner position in response to the closing of said front door, spring means connected with said operating rod and effective when said operating rod is moved to its inner position to exert a force on said locking dog which biases it to its locking position, a push rod movable between inner and outer positions, a push button secured to said push rod within said outer compartment, means biasing said push rod to its outer position, other spring means connected with said push rod and effective when said push rod is moved to its inner position to exert a force on said locking dog which biases it to its unlocking position, latch means effective when said push rod is moved part way toward its inner position for preventing it from returning to its outer position, said latch means being accessible only through the rear door of said casing, and contact means selectively responsive to the latched and unlatched positions of said push rod.

6. A locking device for railway traffic controlling apparatus comprising a casing provided with front and rear doors and divided by means of a partition wall into front and rear compartments, a traffic controlling shaft disposed in said rear compartment and connected with an operating lever disposed in said front compartment, said operating lever being movable between locking and unlocking positions, means preventing the closing of said front door except when said lever occupies its locking position, a locking segment connected to said shaft, a locking dog movable between locking and unlocking positions and effective when said lever and said dog both occupy their locking positions to engage said segment to prevent movement of said lever away from its locking position, electrically controlled means effective when energized to move said locking dog to its unlocking position, an operating rod biased to an outer position and movable to an inner position in response to the closing of said front door, spring means connected with said operating rod and effective when said operating rod is moved to its inner position to exert a force on said locking dog which biases it to its locking position, a push rod movable between inner and outer positions, a push button secured to said push rod within said outer compartment, means biasing said push rod to its outer position, other spring means connected with said push rod and effective when said push rod is moved to its inner position to exert a force on said locking dog which biases it to its unlocking position, latch means effective when said push rod is moved part way toward its inner position for preventing it from returning to its outer position, said latch means being accessible only through the rear door of said casing, and contacts controlled by said operating rod and said push rod.

7. A locking device for railway traffic controlling apparatus comprising a casing provided with front and rear doors and divided by means of a partition wall into front and rear compartments, a traffic controlling shaft disposed in said rear compartment and connected with an operating lever disposed in said front compartment, said operating lever being movable between locking and unlocking positions, means preventing the closing of said front door except when said lever occupies its locking position, a locking segment connected to said shaft, a locking dog movable between locking and unlocking positions and effective when said lever and said dog both occupy their locking positions to engage said segment to prevent movement of said lever away from its locking position, electrically controlled means effective when energized to move said locking dog to its unlocking position, a supporting bracket secured within said rear compartment, an operating rod slidably supported in said supporting bracket and extending into said outer compartment through a hole provided in said partition wall, means for constantly biasing said rod to its outer position, means on said front door cooperating with the outer end of said operating rod when said front door is closed to move said operating rod to an inner position, a lever pivoted at one end and operatively connected at the other end to a rigid arm attached to said operating rod, a leaf spring secured to said lever and effective when said operating rod is moved to its inner position to exert a force on said locking dog to bias said locking dog to its locking position, a push rod slidably supported in said supporting bracket and extending into said outer compartment through a hole provided in said partition wall, a push button secured to the outer end of said push rod, spring means biasing said push rod to an outer position, latch means se-

13

cured to said bracket and cooperating with means secured to said push rod to prevent said push rod from returning to its outer position when it is moved more than a predetermined amount toward its inner position, contacts operated by movement of said push rod from its outer to its latched position, and other spring means connected with said push rod and effective when said push rod is moved to its inner position to exert a force on said locking dog which biases it to its unlocking position, said other spring means being weaker than said leaf spring.

7. A locking device for railway traffic controlling apparatus comprising a casing provided with front and rear doors and divided by means of a partition wall into front and rear compartments, a traffic controlling shaft disposed in said rear compartment and connected with an operating lever disposed in said front compartment, said operating lever being movable between locking and unlocking positions, means preventing the closing of said front door except when said lever occupies its locking position, a locking segment connected to said shaft, a locking dog movable between locking and unlocking positions and effective when said lever and said dog both occupy their locking positions to engage said segment to prevent movement of said lever away from its locking position, electrically controlled means effective when energized to move said locking dog to its unlocking position, a supporting bracket secured within said rear compartment, an operating rod slidably supported in said supporting bracket and extending into said outer compartment through a hole provided in said partition wall, means for constantly biasing said rod to its outer position, means on said front door cooperating with the outer end of said operating rod when said front door is closed to move said operating rod to an inner position, a lever pivoted at one end and operatively connected at the other end to a rigid arm attached to said oper-
